UNITED STATES PATENT OFFICE.

ALBERT E. THOMPSON, OF AURORA, OHIO.

RAILWAY-TIE AND RAIL-FASTENER.

1,097,270.

Specification of Letters Patent.

Patented May 19, 1914.

Application filed February 6, 1914. Serial No. 816,867.

To all whom it may concern:

Be it known that I, ALBERT E. THOMPSON, a citizen of the United States, residing at Aurora, in the county of Portage and State 5 of Ohio, have invented a new and useful Railway-Tie and Rail-Fastener, of which the following is a specification.

My invention relates to improvements in railway ties and more particularly to devices for fastening railway rails to the ties.

The objects of the invention are, to generally improve railway ties and rail fasteners, and to provide a fastening device for the rails which will be simple and easily 15 made, easily applied by unskilled workmen, strong, durable and capable of frequent fastening and unfastening of the rail without permanent injury to the tie and at comparatively small expense. These objects, together with other objects, apparent to those skilled in the art, may be attained by the construction illustrated in the accompanying drawings, although the invention may be embodied in other forms, the construction 20 illustrated being chosen by way of example.

In the drawings Figure 1 is a top plan view of one end of a railway tie embodying my invention and showing a rail in dotted lines fastened to said tie. Fig. 2 is a longitudinal, vertical section through the tie, taken on the line 2—2 of Fig. 1. Fig. 3 is a perspective view of one of the expansion-spikes. Fig. 4 is a perspective view of the expandible member of said spike, the expanding member being removed. Fig. 5 is a perspective view of the expanding member. Fig. 6 is a perspective view of one of the expansion-spike sockets. Fig. 7 is a vertical sectional view of one of the expansion sockets with an expansion-spike arranged therein and a portion of the base flange of a rail shown in dotted lines, the expansion-spike not having been driven down or expanded. Fig. 8 is a similar view 35 of the same elements showing the spike in driven or expanded condition.

Throughout the several views similar reference numerals indicate similar parts.

More specifically describing the construction disclosed in the said drawings, the numeral 1 indicates the concrete body of the tie provided with the spaced, reinforcing rods 2 of any desired form.

The numeral 3 indicates, generally, the expansion sockets, at least one of which

should be arranged upon each side of the base flange of the rail 4.

It will be understood that only one end of the tie and only one rail is shown in the drawings, the other end of the tie being similarly 60 constructed and the length of the tie being determined by the gage of the railway. It will also be understood that the tie may be made of any shape desired and that more than one of the expansion sockets may be 65 arranged upon each side of the rail, as desired.

Each socket is preferably formed of metal and is provided with a central barrel portion 5 provided with two spaced circular flanges 6. In the drawings I have shown these flanges provided with the reinforcing rod apertures 7 adapted to receive the ends of the rods 2, as illustrated in Fig. 2. The top face of the barrel portion 5 is preferably arranged flush with the top surface of the tie and a vertically disposed spike aperture 8 extends through the top face into the body of the barrel portion for a considerable proportion of its length, there being sufficient solid body of the barrel portion remaining beyond the bottom of said aperture 8, however, so as to constitute a substantial bottom or head against which the expansion spike may be driven, as hereinafter described. It should be noted that the spike aperture 8 at its upper end is square in cross section, but that two of the walls of said aperture diverge from each other, from the top to the bottom of the aperture, so that 70 said aperture is wider at the bottom in the direction transverse to the length of the tie, while maintaining a uniform width from top to bottom in the direction of the length of the tie. In the case of concrete ties provided 75 with the expansion sockets described the flanges serve to very thoroughly anchor the sockets to the ties and in all cases said sockets should be carefully arranged so as to have the divergent walls disposed, as above 80 described, so as to properly receive and accommodate the expansion spike.

The expandible member of the expansion spike is preferably formed of iron, steel or other suitable metal, and is provided with 105 a head 9 shaped in accordance with the requirements, the drawings showing a head of the well known railway spike construction. Extending down for a short distance from the head 9 is the integral stem portion 110

10 which is preferably square in cross section and adapted to closely fit within the upper portion of the aperture 8 in the expansion socket. Formed integrally with the 5 stem portion 10 is the downwardly extending bifurcated portion 11 constituting the expandible portion of the expandible member. The bifurcated portion is produced by a wedge shaped cleft 12 wider at the lower 10 end than at the upper end and terminating at the upper end in the cylindrical or barrel shaped recess 13. Adjacent the extreme lower end of the expandible member the cleft 12 is provided with the bulbous recess 13 defined at its bottom end by the inwardly 15 projecting ledges 15 provided on their undersides with inclined faces at 16. It should be noted that the cleft 12 extends through the expandible member in the direction 20 of the length of the head 9, so that the two parts of the bifurcated portion may expand laterally with reference to the longitudinal, median, vertical plane of said head. The expanding member, which is 25 most clearly illustrated in perspective in Fig. 5, is preferably formed of a softer metal, such as lead, and is provided with a wedge portion 17, head 18 and bulbous portion 19 adapted to conform to and be 30 received into the cleft 12, recess 13 and bulbous recess 14, respectively. Formed integrally with the bulbous portion 19, however, and connected thereto by the neck 20, adapted to lie between the ledges 15, is the 35 head 21, the upper surfaces 22 of which lie against the inclined faces at 16, the body of said head 21 being of the same cross section as the stem portion 10 of the expandible member.

40 In fastening the rail to the tie the flange 4 is arranged with its edge in line with the edge of the aperture 8 and the expansion spike is then inserted into said aperture with the head 9 overlying said flange, as 45 illustrated in Figs. 1 and 2. The spike is then driven down by vertical blows upon the head 9, thus driving the metal of the head 21 upwardly between the ledges 15 into the bulbous recess 14 of the bifurcated portion 50 of the expandible member. The inclined faces at 16 serve to direct the metal of the head 21 inwardly and to move the two parts of the bifurcated portion outwardly into engagement with the two divergent walls of 55 the aperture 8. In accordance with the predetermined location of the head 9 with reference to the upper face of the socket 3 when the spike is fully driven the head 21 may be made longer or shorter, there being 60 no necessity, however, for having a variety of lengths of expandible members. Accordingly, when the proper length of head 21 is used and the spike has been driven down to the point desired, the members will assume the fully expanded position, illus-

trated in Fig. 8, whereby a firm and substantial fastening will be produced. It will be noted that any side strain on the rail will be firmly resisted by the fastening because of the fact that the parts of the 70 bifurcated portion are held from side to side of the aperture 8 in the direction of such transverse strain.

When desired the expanded spike may be forcibly withdrawn from the socket 3 by 75 the application of sufficiently powerful pulling force exerted upwardly upon the head 9. In order to be withdrawn the metal of the expanding member must be forced downwardly out of the bulbous recess 14 by the inward pressure upon the bifurcated 80 portions of the expanding member. It will therefore be understood how firmly the spike will resist extraction, although such extraction I have found to be perfectly practicable by the application of sufficient force intelligently applied. In some instances such extraction may so injure the expanding member as to render the same unfit for further use until recast, but the expandible 90 member remains uninjured and, when provided with an appropriate expanding member may be used again with perfect success.

It should be here noted that the inwardly projecting ledges 15 are of extreme importance in firmly grasping the expanding member during the process of extraction so that both the expandible and expanding members may be removed together, leaving the aperture 8 entirely free to receive 100 another or the same expansion spike when it is desired to again fasten the rail.

Although the drawings and above specification disclose the best mode in which I have contemplated embodying my invention, 105 and one of the many practicable applications thereof, I desire to be not limited to the details of such disclosure nor to the exact application of the principles of the invention set forth, for many changes in 110 form and construction may be made, as circumstances require or experience suggests, and many other applications of the principles of my invention may hereafter appear practicable, without departing from 115 the spirit of the invention, within the scope of the appended claims.

I claim:—

1. A fastening device comprising, in combination, a fixed member provided with an inwardly expanded aperture having an inner end wall, a fastening member adapted for insertion into said aperture and provided at its inner end with a furcated portion and an expanding portion adapted to be driven against said end wall and to expand between the separated members of said furcated portion, whereby to cause said separated members to engage the lateral walls of said expanded aperture and resist extraction. 120 125 130

2. A fastening device comprising, in combination, a fixed member provided with an inwardly expanded aperture, having an inner end wall, a fastening member formed of a relatively hard expandible portion and a relatively soft expanding portion, said expandible portion furcated at its inner end and said expanding portion arranged between the spaced members of said furcated portion and extending beyond the inner end thereof, said expanding member adapted to be driven against said end wall and produce expansion of said expandible portion, whereby to resist extraction.
- 15 3. In an expansion fastening device, an expanding member comprising a furcated expandible portion formed of relatively hard material and an expanding portion arranged between the furcations thereof and extending beyond the same, said expanding portion formed of relatively soft material and adapted, when expanded, to distend said furcations.
4. In an expansion fastening device, an expanding member comprising a furcated expandible portion formed of relatively hard material, the ends of said furcations being inwardly inclined and an expanding member formed of relatively soft material, arranged between said furcations, and having a head portion extending beyond the said inclined ends, whereby said expanding member may be driven into a position between said furcations, said inclined ends being adapted to lead the material comprising said head into a position between said furcations in the expansion of said expandible member.
5. A fastening device comprising, in combination, a fixed member provided with an inwardly expanded aperture, having an inner end wall, a fastening member formed of a relatively hard expandible portion and a relatively soft expanding portion, said expandible portion furcated and provided with inwardly extending ledges, said expanding portion located between said furcations and extending beyond the ends thereof, said expanding portion adapted to be driven into position between said furcations whereby to expand the same to engage the walls of said

expanded aperture to resist extraction and said ledges adapted to engage said expanding portion to retain the same in connection with said expanding portion during the process of forcible extraction.

55

6. A fastening device comprising, in combination, a fixed member provided with an inwardly expanded aperture having an inner end wall, and a fastening member formed of a relatively hard expandible portion provided with a wedge-shaped cleft opening through the bottom end of said expandible portion, and a relatively soft expanding portion adapted to fit within said cleft and provided with an integral head extending beyond the lower end of said expandible portion, said fastening member adapted to be inserted into the expanded aperture of said fixed member and said expanding portion adapted to engage said end wall and to be forced upwardly within said cleft when said fastening member is driven downwardly against said end wall.

60

65

70

7. A device of the character described comprising, in combination with a reinforced concrete tie, a rail fastening device comprising, in combination, a fixed member of relatively hard material adapted to be embedded in the concrete body of said tie and connected to the reinforcing members thereof, said fixed member provided with an inwardly expanded aperture having an inner end wall, and a fastening member formed of a relatively hard expandible portion and a relatively soft expanding portion connected to each other, said expanding portion adapted to engage said end wall, when said fastening member is inserted in said expanded aperture, and said expanding portion adapted to expand said expandible portion when said fastening member is driven forcibly against said end wall.
